(57) **CLAIM**

The ornamental design for a door latch, as shown and described.

DESCRIPTION

FIG. 1 is a front perspective view of a door latch showing the new design;

FIG. 2 is a left-side, three-quarter perspective view thereof; and,

FIG. 3 is a right-side, three-quarter perspective view thereof. The broken line showing of the associated appliance is included for the purpose of illustrating environmental structure and forms no part of the claimed design.
